UNITED STATES PATENT OFFICE

EVA L. BURNHAM, OF TACOMA, WASHINGTON

COLLAR-HOLDING DEVICE

Application filed June 26, 1930. Serial No. 464,060.

This invention has reference to a novel and useful device for holding a collar in place and the objects of the invention are first to provide means for preventing the collar from wrinkling, second to prevent the points of the collar from curling, and third to provide a device adaptable to fit collars of varying point lengths.

Other objects of the invention are to provide a device of the character above specified which is efficient and simple in operation, easily attached in place or removed, and which can be manufactured at small cost.

Various other objects and advantages of the invention may appear from the following detailed description thereof, considered in connection with the accompanying drawings, wherein:

Figure 1 is a view illustrating the device applied to a shirt collar, and

Figure 2 is a plan view of the device.

The device is preferably made of tinned spring steel wire so as not to rust or corrode and, as shown in the drawings, the device is formed from a single length of wire which is bent upon itself to provide a substantially elongated cross bar 1 and side legs or extensions 2 adjacent relatively opposite ends of the cross bar and converging toward their free ends which are respectively pointed as shown at 3. At their opposite ends the legs 2 extend laterally beyond the cross bar and are connected in spaced relation to the bar in the manner illustrated so as to provide short retaining fingers 4. The finger forming section of the wires are bent upon themselves, as shown at 5 to provide relatively large spring loops or knuckles which serve to tension the legs 2 and also to permit the leg to be moved outwardly with respect to the bar for adjusting the device to collars of varying point lengths.

As shown in Figure 2, the device is somewhat triangular in form after the bending operations are completed, and the inclination

of the fingers 4 corresponds with their respective legs 2 so that each constitutes practically a continuation of the other. Each leg 2 is, moreover, provided in proximity to the bar 1 with spring knuckle joints hinged for permitting the lower or outer section of the legs to be adjusted relative to the inner or upper sections.

By reason of joints 5 and 6, the legs 2 can be variously adjusted for lengthening or shortening the distance of the points 3 below the cross bar 1. As is pointed out, each leg is bent to provide a circular loop 7 around the points to prevent the latter from snagging or tearing the collar after being attached to the collar point. Inwardly of the pointed end each arm is provided with a bend 8 constituting a finger hold. The tensioning springs 5 and 6 also prevent changing or bending of the device in use.

The device is adapted to be used in the manner illustrated in Figure 1 and is inserted between the flaps of the collar with the cross bar extending under the tie knot and the spring fingers 4 overlapping the necktie band. The tie bar 1 and connected parts are of proper curvature to conform to the curvature of the collar. Points 3 of the legs are inserted in the underside of the collar tips preferably at the end to hold the collar tips in place. In Figure 2 the device is illustrated with its parts adjusted for use with collars having long points or tips and in Figure 1 is shown adjusted for use with short pointed collars.

From the foregoing it is thought that the operation and advantages of the invention will be readily understood and that the invention is also susceptible to various modifications and changes within the scope of the appended claim.

Having thus described the invention, what is claimed is:

A collar support formed of a continuous strand of spring wire and comprising a bar

having its intermediate part adapted to extend under the knot of a necktie, angular fingers terminating adjacent the points of the collar and extending from the bar and pointed for penetrating the collar material and necktie clamping members at the juncture of the bar and the fingers formed by coiling the wire whereby to insert the band between the convolutions thereof.

10 In testimony whereof I affix my signature.
EVA L. BURNHAM.
